UNITED STATES PATENT OFFICE.

ERNEST BARBER, OF PATERSON, NEW JERSEY.

GAUGE FOR LOOMS.

Application filed May 23, 1925. Serial No. 32,299.

To all whom it may concern:

Be it known that I, ERNEST BARBER, a citizen of the United States, residing at Paterson, in the county of Passaic and State 5 New Jersey, have invented certain new and useful Improvements in Gauges for Looms, of which the following is a specification.

It is known to the operators of looms that certain defects in weaving occur which are 10 due to some of the reciprocating parts, as the lay structure or the reed thereon, not assuming accurately a given position at the end of the working stroke, as by overreaching or underreaching the same or being 15 skewed with relation thereto, caused either by improper initial adjustment in setting up the loom or by the parts getting out of adjustment in time. The object of this invention is to provide means whereby faulty 20 adjustment of this character can be readily detected and its correction facilitated. The invention is not limited in its application to looms but may be used in connection with other machines including reciprocating 25 parts.

In the drawing,

Fig. 1 shows in plan the forward part of a loom, with the device of my invention arranged thereon;

Fig. 2 is a vertical sectional view of said part of the loom, showing the device in side elevation; and

Figs. 3 and 4 illustrate details.

1 designates the loom frame, which may 35 be regarded as including the breast-beam 2, and 3 are the lay-swords and 4 the lay or batten of the lay structure which is reciprocated in the usual way through the pitmen 5 pivotally connected therewith. The lay 40 structure is supposed to be mounted so that, at least when it is in the fully forward or beating-up position, it will also be perpendicular to the path of advance of said sheet of warp and woven goods, and this is true 45 of also of the reed suitably arranged in a recess 4^a at the back of the batten and held normally bearing against the latter by springs 4^b, being pivoted at 3^a in brackets 3^b; and the reed is further supposed to exert 50 a certain amount of pressure (due to the springs) on the fell of the fabric. But defects occur frequently in weaving that are due to one or the other of the lay structure and reed being not accurately in the position 55 it should have at the end of the working stroke. Now for detecting such irregulari-

ties and facilitating correcting them I provide the means hereinafter embodied in the claims and one example of which I now describe in detail:

A support is provided here consisting of a base-strip 7 and a plurality of clips 8 secured thereon. The support is intended in the present case to have a bearing on the forward face of the breast-beam and for 65 this purpose the clips 8, which may be formed of strap metal, have their forward ends 8^a bent downward so as to stand in a vertical plane when the support is seated on the breast-beam; the clips are shown extending 70 over the base-strip and they are at right-angles thereto (said strip being straight), the means to secure them to the base-strip being shown as screws 9. Their upper ends are re-bent to form crotches open toward 75 the batten, the crotches having set-screws 10 arranged vertically and at their closed ends adjusting screws 11.

A gauge-including structure is carried by the mentioned support or supporting means, 80 the same including with the gauge a straight-edge strip 12 which is received by the crotches and stands in contact with the adjusting screws and held by the set-screws; the straight-edge of this strip adjoins the 85 batten. Any suitable gauge may be used having a movable gauge-actuator, that shown being a dynamometer of the piston-and-cylinder type. 13 is its cylinder, 14 the piston or gauge-actuator, and 15 the case of 90 the gauge-proper having a dial 17 and a pointer 18 movable by pressure of a fluid contained in the gauge and admitted from the cylinder to the interior of the case by a tubular connection 16. The gauge has means 95 to hold it in a definite position on the strip 12, as a crotch or cross-groove 19 formed in the closed end of the cylinder and fitting snugly over the inward or straight edge of 100 said strip.

The free end of the piston or plunger is suitably equipped to receive the impact of the reed or other moving part, and for this purpose I preferably provide it with interchangeable adapters. One such adapter, intended to receive the impact of the reed dents, is a blade 20 which is held in a cross-groove 21 of the piston by a removable pin 22 so that the blade is at right-angles to the piston. Or a cap-like head (Fig. 4) may 105 be fitted snugly over the free end of the piston, being adapted for engagement with 110

some surface offering stouter resistance than the reed dents.

24 is a truss for stiffening the strip 12.

In use the operator places the support in 5 fixed position on some fixed part of the machine frame, as the breast-beam, usually securing it by some means, as the clamps 25 shown by broken outline in Fig. 1 as engaging the outer face of the breast-beam 10 and the lugs 8^a, the strip 12 being adjusted and secured where adjusted so that its straight-edge is perpendicular to the path taken by the sheet of warp and woven fabric as it is advanced in the process of weaving. The gauge is then fitted to the support 15 so that it abuts squarely against the straight-edge and the piston and cylinder are perpendicular to said edge. The desired deduction is then attained in an obvious 20 manner by moving the part to be tested toward the piston. The operator knows, for example, that in the fully forward position of the batten the pressure of the reed should cause the pointer to be moved to a certain 25 point on the scale of the gauge; if it does not adjustment of the springs 4^b is effected. Again, if the two lay-swords, or the two ends of the batten or of the reed, etc., do not at 30 the end of the forward stroke come to the same line perpendicular to the path of advance of the sheet of warp and woven fabric this will be revealed by the gauge upon putting it in operation first at one point on 35 the strip 12 and then at a more or less remote point.

While so far as adjustment toward and from the part to be tested is concerned I have treated 7—8 as a support or supporting means and the gauge and rail 12 as a gauge- 40 including structure it will also be apparent that so far as lateral or transverse adjustment is concerned 7—8—12 may be regarded as a carrying structure on which (along said straight-edge) the gauge is capable of such 45 adjustment.

Having thus fully described my invention what I claim and desire to secure by Letters Patent is:

1. In a means for detecting irregularity in the position of a reciprocating part relatively to a fixed part of a machine when the reciprocating part is at the limit of its working stroke, the combination of a support adapted to be fixed on one such part of the machine and a gauge-including structure including a movable gauge-actuator adapted to be engaged and moved by the other part, said structure being adjustable on the support substantially lengthwise of the path of movement of the reciprocating part. 50 55 60

2. In a means for detecting irregularity in the position of a reciprocating part relatively to a fixed part of a machine when the reciprocating part is at the limit of its working stroke, the combination of a carrying structure having a straight-edge and adapted to be fixed on one such part of the machine with the straight-edge transverse of the path of reciprocation of the reciprocating part and a gauge including a movable 70 gauge-actuator adapted to be engaged and moved by the other of said parts, said gauge being shiftable along said straight-edge. 65 70

3. In a means for detecting irregularity in the position of a reciprocating part relatively to a fixed part of a machine when the reciprocating part is at the limit of its working stroke, the combination of supporting means adapted to be fixed on one such part of the machine, a straight-edge strip arranged transverse of the path of reciprocation of the reciprocating part and adjustable on said means substantially lengthwise of said path, and a gauge including a movable gauge-actuator adapted to be engaged and moved by the other of said parts, said gauge being adjustable on said strip along 80 85 88 said straight-edge.

In testimony whereof I affix my signature.
ERNEST BARBER.
